James Paterson's Design for Oil Cloth
assigned to

R.H. & B.C. Reers
PATENTED

3782

DEC 7 1868

United States Patent Office.

JAMES PATERSON, OF ELIZABETH, ASSIGNOR TO RICHARD H. REEVE AND BENJAMIN C. REEVE, OF CAMDEN, NEW JERSEY.

Design No. 3,782, dated December 7, 1869.

DESIGN FOR A FLOOR OIL-CLOTH PATTERN.

The Schedule referred to in these Letters Patent and making part of the same.

I, JAMES PATERSON, of Elizabeth, in the county of Union, and State of New Jersey, have invented and produced a new and original Design for Oil-Cloth, of which the following is a specification.

The nature of my design is fully represented in the accompanying photographic illustration, to which reference is made.

The octagon figures A are joined together as represented.

All the octagons have borders *a* and margins *b*.

The borders are of the same color.

The margins of the octagons, which are in diagonal line, running one way, are of a white or light color, and of those running in the opposite direction, of a dark color.

The middle part C of the latter has a dark background, and that of the former a light background.

Each octagon has a central figure, *d*, of different color.

The figures running in diagonal lines, in one direction, have like colors, and those running in the opposite direction, uniformly other colors.

The squares B, between the octagons, have in them the form of a St. Andrew's cross.

Having thus described my improvement in oil-cloths,

What I claim as my invention, is—

The design for oil-cloths, as shown.

In testimony that above is my invention or discovery, I have hereunto set my hand and seal, this 15th day of November, 1869.

Witnesses: JAS. PATERSON. [L. S.]

A. D. PATERSON,

B. F. VINCENT.
